UNITED STATES PATENT OFFICE

GENEVIEVE BRUER, OF SAN FRANCISCO, CALIFORNIA

HATBOX

Application filed December 10, 1928. Serial No. 324,939.

My invention relates to containers for hats and may be embodied either in a shipping box of cardboard construction or in a travelling or storage hat case.

- 5 The principal object of my invention is to provide a hat box having a member adapted to hold the hat out of contact with the sides, top, and bottom of the box, which can be manufactured and sold at such low cost 10 as to permit it to be used by merchants as a temporary package for the delivery of hats and to be thrown away thereafter. A second object is to provide a box having a hat holding member which can, if desired, be removed and used to hold a hat in a travelling or storage case. A still further object is to provide a hat holder which can be made of cardboard and shipped flat in knocked down form, thus reducing its cost to a minimum. 15 These and other objects and advantages of the invention will be apparent from the following description, which should be read with the understanding that the form, construction and arrangement of the several parts 20 may be varied, within the limits of the claims hereto appended, without departing from the spirit of the invention as defined therein.

A preferred embodiment of my invention will now be described with reference to the 25 accompanying drawings, wherein:—

Fig. 1 is a plan view of a complete hat box with my holder therein.

Fig. 2 is a vertical section taken on the line 2—2 of Fig. 1.

30 Fig. 3 is a perspective view of the hat holding member removed from the box.

Fig. 4 is a detail of the means for fastening the ends of the hat holding member beneath the base or bottom.

35 In the drawings, the reference numeral 1 designates a box of any shape and type suitable for containing a hat. Within the box is a holder comprising two strips 2 of flexible material bent into approximate U-shape and 40 placed at right angles to each other, adapted to enter the crown of the hat (not shown) and support the same with its brim elevated above the bottom of the box. I prefer to make the strips 2 of cardboard, which has enough resilience to cause them to assume the form

shown in Figs. 2 and 3, with their sides bulging out to resiliently grip the inside of the crown of the hat. The strips may be joined together at the top, but such connection is not necessary.

45 The strips 2 are secured in position preferably by having their ends 3 passed through slots in a false bottom 4 and bent over horizontally between said false bottom and the true bottom 5 of the box. The false bottom 4 may be omitted, in which case the ends 3 of the strips 2 would be passed through the true bottom 5 in a similar manner. This latter construction would be suitable in boxes intended only for the delivery of hats from 50 stores, but where the device is used in more permanent boxes, such as articles of luggage, the false bottom is preferred.

55 The ends 3 of the strips 2 may be fastened, to prevent them from slipping out of place, in any suitable manner. As one example of such fastening, I have shown in Fig. 4 said ends as laced together by a tongue and slot connection 6 similar to that commonly employed at the corners of cardboard boxes. 60 Such connection may be omitted, however, especially when the false bottom 4 is used, the strips 2 being held in place sufficiently by having their ends 3 bent horizontally between the false and true bottoms.

65 It will be appreciated that my device can be made very cheaply of cardboard, and can be shipped flat, consisting only of the two flat strips 2 with or without the flat false bottom 4, which is also preferably made of cardboard. It can be assembled easily and quickly, and forms a device capable of securely holding a hat out of contact with the walls of the box. It is useful not only to the merchant in his shipping boxes, but, when the 70 false bottom is employed, the entire holder may be removed by the purchaser of a hat from the shipping box and placed within a travelling or storage case.

75 It will also be apparent that the height of the hat holding member can be raised or lowered, merely by slipping the ends of the strips 2 in one direction or the other, through the slots in the bottom or false bottom. Thus if the box is to contain a number of hats stacked 80

one upon another, the ends of said strips are pulled downwardly through their slots, thus lowering said strips so that the lowermost hat rests upon or is only very slightly above the bottom of the box.

5 I claim:—

1. The combination with a support, of a hat retaining member including a flexible strip bent substantially in U-shape, the free ends of said strip being inserted through slots in said bottom and bent inwardly towards one another, thereby creating a positive force acting through said strip to maintain an outward bulge in the opposite side walls of the strip above the support.
- 10 2. The combination with a base, of a hat retaining member including a flexible strip bent substantially in U-shape, the free ends of said strip being inserted through slots in said base and bent inwardly towards and secured to one another, thereby creating a positive force acting through said strip to maintain an outward bulge in the opposite side walls of the strip above the base.
- 15 3. The combination with a receptacle having a false bottom, of a hat retaining member including a plurality of flexible strips bent substantially in U-shape, one of said strips disposed over and at an angle to another of said strips, the free ends of said strips being inserted through slots in said bottom and bent inwardly towards one another, thereby creating a positive force acting through said strips to maintain an outward bulge in the opposite side walls of the strips above the false bottom.
- 20 4. The combination with a base, of a hat retaining member including a plurality of flexible strips bent substantially in U-shape, one of said strips disposed over and at an angle to another of said strips, the free ends of each of said strips being inserted through slots in said base and bent inwardly towards and secured to one another, thereby creating a positive force acting through said strips to maintain an outward bulge in the opposite side walls of the strips above the base.

45 In testimony whereof I have signed my name to this specification.
